Howard E. Thompson
ATTORNEY

UNITED STATES PATENT OFFICE

WILLIAM POTTER, OF NEW YORK, N. Y.

DEVICE FOR SETTING THE EDGES OF SCRAPERS

Application filed September 17, 1929. Serial No. 393,227.

This invention relates to a tool or device for use in setting or turning the edges of scraping tools and particularly to devices of this class known as burnishing tools; and the object of the invention is to provide a device of the class specified with means for adjustably and firmly clamping a scraping tool in connection with one part thereof as well as the provision of means for adjustably and movably mounting a burnishing tool in connection with another part thereof, said last named part being adjustable with respect to the first named part; a further object being to provide a device of the class specified having means whereby the angular position of the burnishing tool with respect to the edge of a scraping tool may be varied to control and regulate the turning or setting of the edge of said tool; a further object being to provide a handle member in connection with which a burnishing tool is adjustably and detachably supported; a still further object being to provide a burnishing tool of the class specified having an irregular cross sectional contour so as to provide a plurality of surfaces of different curvature in the several uses thereof; and with these and other objects in view, the invention consists in a device of the class and for the purpose specified which is simple in construction, efficient in use and which is constructed as hereinafter described and claimed.

The invention is fully disclosed in the following specification of which the accompanying drawings form a part, in which the separate parts of my improvement are designated by suitable reference characters in each of the views, and in which:

Fig. 1 is a plan view of the device indicating the method of its use.

Fig. 2 is a side and sectional view, the sectional being on the line 2—2 of Fig. 1 and part of the construction being broken away.

Fig. 3 is a sectional detail view on the line 3—3 of Fig. 2.

Fig. 4 is a detail view illustrating the use of the edge portion of the burnishing tool.

Fig. 5 is a plan view of one end of a scrap-

ing tool illustrating the method of turning the edge thereof; and

Fig. 6 is a side view of one end of a scraping tool illustrating edges turned on opposite side faces thereof.

In carrying my invention into effect, I have shown in Figs. 1 and 2 of the drawings, one form of construction which consists of three parts, namely a vise part 10, a lever part 11 and a handle member and burnishing tool supporting part 12. The part 10 consists of a member 13 substantially L-shaped in cross sectional form so as to be supported upon a table, work-bench or the like indicated at 14 in Fig. 1 of the drawings.

The downwardly extending plate 13a of the member 13 constitutes one jaw of the vise, the other jaw being independent of and movable relatively to the jaw 13 by winged nuts 16 mounted upon threaded ends of rods 17, the latter being secured to the end portions of the jaw 13a and extending therefrom in the form of outwardly and laterally bent arms adapted to lie upon the surface of the bench or table 14 and being in alignment with the lower surface of the horizontal U-shaped portion 13b of the part 10. A winged set screw 18 is also arranged upon the jaw 15 at the lower end thereof and is adapted to engage the face of a scraping or other tool 19 to prevent any possible shifting of the tool within said jaws.

The lever part 11 in the construction shown consists of a tubular rod 20, one end of which is flattened as seen at 21 and is arranged within the channel of the U-shaped part 13b and is pivoted thereto by a pivot pin 22 whereas the outer end portion of said tube is provided on its upper surface with a plurality of spaced apertures 23 adapted to receive a pin 24 on a lever bar 25, the latter being pivoted within the channel of the U-shaped portion 13b as seen at 26, note Fig. 1.

The bar 25 is adapted to support the tube 20 in different positions of adjustment such as is shown in full lines in Fig. 1 of the drawings, or as partially indicated in dotted lines in said figure, for the purpose of shifting a pivot rod 27 with respect to the pivot 22 in the several uses of the device. The rod 27 is secured to

the tube 20 and projects above the upper surface thereof and is externally threaded to receive a winged nut 28 and an adjacent lock nut 29 as well as a nut 30 which limits the downward movement of the handle member 12 on said pivot rod.

One end of the handle member 12 which is tubular in form in the construction shown is provided with an aperture 31 in its upper wall to freely receive the pivot rod 27 and with an elongated aperture 32 in its opposite or lower wall to permit the free vertical swinging of the handle with respect to said rod, this construction also permitting the rotation of the handle member on said rod as will be apparent.

Mounted in connection with the handle member 12 adjacent the pivoted end thereof is a supporting ring 33 arranged on the lower face of the handle member and detachably supported in connection therewith by a nut 34 arranged upon a threaded shank 35 which passes through the handle member, the ring 33 being adapted to support the outer end of a burnishing tool 36 in several positions of its adjustment with respect to the handle member 12.

The cross sectional form of the shank of the burnishing tool 36 is preferably irregular to provide four surfaces of contrasting contour or curvature which are designated at α , α_1 , α_2 and α_3 in Fig. 3 of the drawings, and any one of these surfaces may be arranged to operate upon the edge of the tool 19 in the operation of turning or setting the same. To accomplish this result, the handle member 37 of the tool 36 is provided with four surfaces arranged in longitudinal alignment with the surfaces α — α_3 inclusive and with two apertures 38 arranged at right angles to each other and exposed through the surfaces of said handle member so as to receive a securing bolt 39 passed through the handle member and said apertures 38, the handle portion of the tool being supported against displacement by a nut 40 on said bolt as clearly seen in Fig. 2 of the drawings.

It will be noted that the lower surface of the tube 12 is in alignment with the lower surface of the U-shaped portion 13b so that in the use of the device, the tube 20, U-shaped portion 13b and arms 17 will lie flatly upon the upper surface of the table or workbench 14 whereas the jaw 13a may be moved into engagement with one edge of said table or work-bench, and in this way, the tool may be firmly supported in the use thereof.

After the scraping tool 19 has been fixed in position between the jaws 13a and 15 and the burnishing tool 36 properly adjusted and secured to the handle member 12, said tool may be moved over the upper or protruding edge of the scraping tool 19 to turn or set the edge thereof, sufficient downward pressure being exerted to accomplish this result.

When it is desired to turn a comparatively wide edge on the tool 19, the nuts 28 and 29 are arranged relatively high upon the pivot rod 27 in order to provide a decided inclination of the burnishing tool with respect to the edge of the scraping tool somewhat in the manner indicated in Fig. 2 of the drawings, and when this result is not necessary, the nuts 28 and 29 may be lowered upon the rod 27 to reduce this inclination. It will be apparent that in moving the handle member and the burnishing tool 36 thereon over the upper edge of the scraping tool, said burnishing tool travels in an arc-shaped path, thus producing a sliding action of the tool 36 with respect to the edge of the tool 19 facilitating the production of a turned edge 19a, note Fig. 5, which protrudes to a greater extent centrally of the tool than at the side edges thereof which is a desirable condition in scraping tools. This result is further facilitated by governing the pressure of the burnishing tool and further by adjusting the lever part 11 into its several angular positions which will change the arc path of travel of the tool 36 with respect to the tool 19. As indicated in Fig. 6 of the drawings, both side edges of the scraping tool may be turned so that the tool may be reversed in its use in scraping floors or other surfaces and the pointed end 36a of the burnishing tool 36 may be used to sharpen the turned edge 19a as in other tools of this class.

From the foregoing, it will be apparent that the distinctive features of my invention reside first in the provision of a device in connection with which a scraping tool may be firmly supported in the operation of turning the edge thereof, and further a device which will permit the application of sufficient pressure of the burnishing tool upon the edge of the scraping tool to properly turn or set the edge thereof, and still further to governing and controlling the angular arrangement of the burnishing tool with respect to the edge of the scraping tool and to control the swinging or sliding movement of the burnishing tool in the operation thereof and especially in the provision of a device which will accomplish the results above specified which is of simple and practical construction.

In this connection it is also to be noted that the arms 17 perform an important function in preventing the rocking or displacement of the vise part 10 with respect to the table or other support 14 in the swinging movement of the burnishing tool especially when at the side edge portions of the scraping tool. Still further, it is to be noted that by using the comparatively sharp surface α_3 of the burnishing tool 36, more efficient results can be accomplished in the operation of turning the edge of the scraping tool than when a surface such as α or α_1 is used. In

some instances, it is desirable to provide a fine edge on the scraping tool whereas in other cases a very coarse edge is desirable especially when heavy scraping is desired.

5. It will therefore be seen that with my improved device, the edges of scraping tools may be formed in the most efficient and practical manner.

It will be understood, that while I have 10 shown and described certain details of construction for carrying my invention into effect, that I am not necessarily limited to the construction herein shown and described, and 15 various changes therein and modifications thereof may be made within the scope of the appended claims without departing from the spirit of my invention or sacrificing its advantages.

Having fully described my invention, what 20 I claim as new and desire to secure by Letters Patent, is:—

1. A device of the class described comprising a workpiece supporting part, means for securing a workpiece in connection with said 25 part, a burnishing tool supporting member adjustably and pivotally mounted in connection with said first named part and adapted to move over the surface of a workpiece supported in said part, means for detachably and 30 adjustably supporting a burnishing tool in connection with said member, and the cross sectional form of the blade of said tool being irregular to provide a plurality of longitudinal surfaces of different curvatures.

35. 2. A device of the class described comprising a vise part in connection with which a workpiece is adapted to be supported, said vise part comprising relatively movable jaws, the arrangement of which is such as to form 40

a workpiece receiving chamber opening through upper and lower edges of said jaws, a rod-like handle member, means for pivotally supporting one end of said handle member to permit its swinging movement over the 45

upper edge of said jaws, said handle member being movable vertically on said means for adjusting said handle member vertically with respect to said jaws to vary the inclination of the handle member with respect thereto, a tool arranged longitudinally of and beneath 50 said handle member and means for detachably supporting said tool in connection with the handle member.

55. 3. A device of the class described comprising a vise part in connection with which a workpiece is adapted to be supported, said vise part comprising relatively movable jaws, the arrangement of which is such as to form a workpiece receiving chamber opening 60

through upper and lower edges of said jaws, a rod-like handle member, means for pivotally supporting one end of said handle member to permit its swinging movement over the upper edge of said jaws, said handle member 65 being movable vertically on said means for

adjusting said handle member vertically with respect to said jaws to vary the inclination of the handle member with respect thereto, a burnishing tool, the blade of which is arranged longitudinally of said handle member, 70 means for detachably supporting said tool in connection with the handle member, the cross sectional form of the blade of said tool being irregular to provide a plurality of longitudinal surfaces of different curvatures, and 75 means for adjusting the tool with respect to the handle member to arrange the different surfaces in position to operatively engage a workpiece supported in the jaws of the vise part. 80

4. A device of the class described comprising a vise part in connection with which a workpiece is adapted to be supported, said vise part comprising relatively movable jaws, the arrangement of which is such as to form 85 a workpiece receiving chamber opening through upper and lower edges of said jaws, a rod-like handle member, means for pivotally supporting one end of said handle member to permit its swinging movement over the upper edge of said jaws, said handle member being movable vertically on said means for adjusting said handle member vertically with respect to said jaws to vary the inclination of the handle member with respect thereto, a 90 burnishing tool, the blade of which is arranged longitudinally of said handle member, means for detachably supporting said tool in connection with the handle member, the cross sectional form of the blade of said 95 tool being irregular to provide a plurality of longitudinal surfaces of different curvatures, means for adjusting the tool with respect to the handle member to arrange the different surfaces in position to operatively engage a workpiece supported in the jaws of the vise part, and said first named means involving a lever pivotally and adjustably supported in connection with the vise part. 100

5. The combination with a device for turning the edges of scrapers comprising a vise part for clamping a scraper in position to expose the edge to be turned and a tool supporting member pivotally and adjustably mounted in connection with said vise part, of a 105 burnishing tool adapted to be supported in connection with said member and the cross section of the blade of said tool being irregular to provide a plurality of longitudinal surfaces of different curvatures adapted to operatively engage the edge of the scraper and to control the extent of turning of such edge, and means for adjustably supporting the burnishing tool in connection with said member to arrange the different longitudinal surfaces in position to operatively engage the scraper. 110

6. A device of the class described comprising a workpiece supporting frame adapted to be supported upon a work bench, said frame 115

including a vise portion by means of which a workpiece may be clamped thereto, an upwardly extending rod on said frame, a handle member slidably mounted on said rod and capable of rotary and vertical swinging movement on said rod, means adjustably supported on the rod for limiting the upward movement of the handle member with respect thereto to regulate the inclination of the handle member with respect to a workpiece supported in the vise portion of the frame, a burnishing tool arranged longitudinally of said handle member, and means for detachably supporting said tool in connection with the handle member.

7. A device of the class described comprising a workpiece supporting frame adapted to be supported upon a work-bench, said frame including a vise portion by means of which a workpiece may be clamped thereto, an upwardly extending rod on said frame, a handle member mounted on said rod and capable of rotary and vertical swinging movement on said rod, means adjustably supported on the rod for limiting the upward movement of the handle member with respect thereto to regulate the inclination of the handle member with respect to a workpiece supported in the vise portion of the frame, a burnishing tool arranged longitudinally of said handle member, means for detachably supporting said tool in connection with the handle member and means for adjusting the position of said rod with respect to the vise portion of said frame.

8. A device of the class described comprising a workpiece supporting frame adapted to be supported upon a work-bench, said frame involving means for clamping a workpiece in connection therewith, an upwardly extending pivot rod arranged in spaced relation to said clamping means and a tool supporting member mounted upon said rod and adapted to swing thereon to move a tool on said member relatively to a workpiece supported in connection with said frame, said member being movable vertically on said rod to vary the angular position thereof with respect to a workpiece, adjustable means on said rod for limiting the movement of said member thereon, and means for adjusting the position of said pivot rod with respect to said workpiece clamping means.

9. A device of the class described comprising a workpiece supporting frame adapted to be supported upon a work-bench, said frame involving means for clamping a workpiece in connection therewith, an upwardly extending pivot rod arranged in spaced relation to said clamping means and a tool supporting member mounted upon said rod and adapted to swing thereon to move a tool on said member relatively to a workpiece supported in connection with said frame, said member being movable vertically on said rod to vary

the angular position thereof with respect to a workpiece, adjustable means on said rod for limiting the movement of said member thereon, means for adjusting the position of said pivot rod with respect to said workpiece clamping means, and means for adjustably supporting a tool in connection with said member.

In testimony that I claim the foregoing as my invention I have signed my name this 14th day of September, 1929.

WILLIAM POTTER.
